UNITED STATES PATENT OFFICE.

WALTER S. MOODY, OF SCHENECTADY, NEW YORK, ASSIGNOR TO GENERAL ELECTRIC COMPANY, A CORPORATION OF NEW YORK.

INDUCTION ELECTRIC FURNACE.

1,113,134.

Specification of Letters Patent.

Patented Oct. 6, 1914.

Application filed October 18, 1906. Serial No. 339,481.

To all whom it may concern:

Be it known that I, WALTER S. MOODY, a citizen of the United States, residing at Schenectady, county of Schenectady, State 5 of New York, have invented certain new and useful Improvements in Induction Electric Furnaces, of which the following is a specification.

This invention relates to apparatus for melting metals, smelting ores and similar operations, in which an electric current sufficient to cause a melting heat is induced in the material under treatment. To effect this, said material is placed in an annular 15 crucible and arranged to constitute the closed secondary of a transformer, whose primary is arranged concentric with said crucible. A suitable core passes centrally through the crucible. In furnaces of this 20 character which have been heretofore proposed, the primary coil has been a single element, arranged either wholly outside of the crucible or wholly inside the same. Inasmuch as the walls of the crucible must be of considerable thickness to give them strength 25 enough to safely hold the charge of melted material, it follows that the distance between the primary coil and the charge, which forms the secondary coil, is greater 30 than is usual in ordinary transformers. The reactance of the furnace is therefore excessive, and increases with the size of the furnace. In a furnace of this kind if the annular crucible is completely filled with a 35 charge of metal, each primary turn induces its proportional part of the current in the adjacent part of the secondary (the charge); but if the crucible should be but half full, it is evident that the primary turns near the 40 top have no corresponding secondary, and therefore the reactance between these turns and the charge located in the lower part of the furnace must be high. Moreover, the reactance between the charge and the inner 45 and outer parts of the winding is not equal. For purposes of economy, it is desirable to use a high frequency generator. In order, therefore, to enable a higher frequency to be employed to treat a given load, it is necessary to find some way to reduce the reactance if a reasonably high power factor is to be maintained. I find that I can make a 50 large induction furnace which can be operated satisfactorily with commercial frequencies by subdividing the primary coil,

one part being placed inside the crucible and the other part outside. Moreover, by making each part in superposed sections, and connecting all the sections in multiple, the load on the primary will be taken by those 60 sections in the plane of the charge, and the excessive reactance above mentioned will be avoided. Theoretically, the perfect arrangement would be to have every turn in multiple with every other turn, but since 65 this is practically impossible, each part of the winding is divided into a reasonable number of sections.

The accompanying drawing shows an induction furnace embodying my improved 70 construction.

Figure 1 is a vertical diametrical section on line 1, 1, Fig. 2; Fig. 2 is a plan view; Fig. 3 is a diagram of the primary winding; and Fig. 4 is a perspective view of a piece 75 of said winding.

The crucible 1 is composed of refractory material, such as fire brick, and is annular in shape. It is supported on a suitable foundation 2, and is provided with a top plate 80 2' and a removable cover 3 of fire clay or the like, made in segments. A spout 4 is located at some convenient point below the level of the charge in the crucible, and a tap-hole, closed by a plug 5, connects the crucible with said spout for drawing off the molten metal. The thickness of the walls of the crucible is no greater than is necessary to hold the charge 6 safely, in order that the primary coils may come as near to 90 the charge as possible. The charge constitutes a short circuited secondary coil, and is readily melted by the heat generated therein when an alternating current flows through the primary winding.

One leg 7 of a laminated core of the core type passes centrally through the annular crucible, the other leg or legs 8 being outside thereof. A space is left between the central leg 7 and the crucible in which is wound a 100 suitable length of copper conductor, preferably a copper tube 9, having the turns insulated from each other and from the core. A similar coil 10 is wound around the outside of the crucible, and the two tubes are 105 coupled together at 11, Figs. 2 and 3 so as to constitute one continuous tube. At 12 are connections whereby a supply of water can be circulated through the tube to keep it cool. The electric current from the mains 110

13 flows through the walls of the copper tube, or if desired, a stranded cable 14, as shown in Fig. 4, may be provided inside the tube to carry some of the current and thereby allowing a thinner tube to be used to lessen the eddy losses.

Both the inner and the outer coils are divided into superposed sections, separated, if desired, by an insulating diaphragm 15. In 10 the present instance, each coil is divided into two sections, and the four sections are all connected in multiple to the mains 13. Insulating couplings 16 are used to break the tube into electrically separate portions, and 15 the cable 14 also must be similarly interrupted coincidently with the joints in the pipe. The connections with the mains 13 are made by branch conductors 17 attached to the tube at each side of the couplings, as 20 shown in Fig. 3. The outer sections may have a smaller cross-section than the inner because they take less current than the inner, due to the fact that the mutual reactance between them and the secondary is 25 greater than that between the inner sections and the secondary.

What I claim as new and desire to secure by Letters Patent of the United States, is,—

1. An electric furnace comprising a crucible, a core passing through said crucible, and a primary winding divided into two parts connected in multiple with each other, one inside of said crucible and the other outside thereof.

35 2. An electric furnace comprising an annular crucible, a core passing centrally through said crucible, and a primary winding divided into two parts, one inside of said crucible and the other outside thereof, said 40 winding consisting of thin copper tubing suitably insulated.

3. An electric furnace comprising a magnetic core, a primary winding surrounding one leg of said core and divided into two 45 concentric coils connected in multiple with each other, and an annular crucible concentric with and located between said coils.

4. An electric furnace comprising an annular crucible, a core passing centrally 50 through said crucible, and a primary winding concentric with said crucible and divided into sections connected in multiple.

5. An electric furnace comprising an annular crucible, a core passing centrally 55 through said crucible, and a primary winding concentric with said crucible and divided into superposed sections connected in multiple.

6. An electric furnace comprising an annular crucible, a core passing centrally 60 through the same, and a primary winding divided into two parts, one inside of said crucible and the other outside thereof, each

part being composed of sections connected in multiple.

7. An electric furnace comprising an annular crucible, a core passing centrally through the same, and a primary winding divided into two parts, one inside of said crucible and the other outside thereof, each part being composed of sections connected in multiple and superposed.

8. An electric furnace of the induction type comprising a primary winding consisting of a metallic tube with a metallic 75 conductor passing through the same.

9. An electric furnace of the induction type comprising a primary winding consisting of a metallic tube with a stranded metallic conductor passing through the 80 same.

10. An electric furnace of the induction type comprising a primary winding consisting of a continuous metallic tube divided into electrically independent sections, 85 and insulating couplings between said sections.

11. An electric furnace of the induction type comprising an annular crucible, and a primary winding divided into two parts, 90 one inside and the other outside of said crucible, the outer part being smaller in cross-section than the inner, and said parts being connected in multiple.

12. An electric furnace of the induction type comprising a crucible, a core, and a primary winding formed of a plurality of sections connected in multiple with each other and inductively related to said crucible.

13. An exciting winding consisting of sections of tubing electrically connected in multiple with each other, and means for passing a cooling fluid successively through 105 said sections.

14. The combination of a plurality of sections of tubing connected together by electrically insulating joints to form a continuous tube, and electrical connections joining said sections in multiple with each 110 other.

15. An electric furnace comprising a crucible, a core, a primary winding formed of a plurality of sections of tubing electrically connected in multiple with each other and mechanically connected by insulating joints to form a continuous tube, and means for passing a cooling fluid successively through 115 the sections of tubing.

In witness whereof, I have hereunto set 120 my hand this 17th day of October, 1906.

WALTER S. MOODY.
